(57) CLAIM

I claim, the ornamental design for a tube for removing nail polish, as shown and described.

DESCRIPTION

FIG. 1 is a perspective view of a tube for removing nail polish, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view of the nail tube showing a cap with a tube; and,

FIG. 9 is a cross-sectional view taken along line 9-9 in FIG. 6.
